(57) **CLAIM**

The ornamental design for a coffee pot press, as shown and described.

DESCRIPTION

FIG. 1 is a perspective view of the coffee pot press.

FIG. 2 is a side view of the coffee pot press shown in FIG. 1.

FIG. 3 is another side view of the coffee pot press shown in FIG. 1.

FIG. 4 is front view of the coffee pot press of FIG. 1.

FIG. 5 is a rear view of the coffee pot press of FIG. 1.

FIG. 6 is a top view of the coffee pot press of FIG. 1; and,

FIG. 7 is bottom view of the coffee pot press of FIG. 1.

The present application is directed to the design illustrated in the drawings. The broken line portions of the disclosure are for illustrative purposes only and form no part of the claimed design.

1 Claim, 5 Drawing Sheets
